UNITED STATES PATENT OFFICE.

JAMES L. SHARP, OF NEW YORK, N. Y.

OIL-STOVE.

SPECIFICATION forming part of Letters Patent No. 259,055, dated June 6, 1882.

Application filed February 14, 1882. (No model.)

To all whom it may concern:

Be it known that I, JAMES L. SHARP, of New York, in the county and State of New York, have invented an Improved Oil-Stove, 5 of which the following is a specification.

Figure 1 is a vertical central section through my improved oil-stove on the plane of the line *c c*, Fig. 2. Fig. 2 is a horizontal section of the same on the plane of the line *k k*, Fig. 1. 10 Fig. 3 is a detail vertical section on the plane of the line *c k*, Fig. 2. Fig. 4 is a front view, partly in section, of the stove, the line *q q*, Fig. 2, indicating the plane of section.

This invention relates to certain improvements in the arrangement of the oil-reservoir of a coal-oil stove and of the cover or covers for the same.

The first object of the invention is to so arrange the oil-reservoir in a coal-oil stove, with 20 reference to currents of air that are allowed to pass over it, that the danger of overheating the oil will be altogether avoided. Another object is to facilitate the connection of the several parts of the stove, so as to give access to 25 each for inspection, cleaning, and repair, also to simplify the manner of feeding the stove with oil.

The invention consists in a new arrangement of oil-chamber with reference to a hinged cover, 30 air-chamber, and surrounding framing, and with reference to the feed or supply tube, all as hereinafter more fully described.

In the drawings, the letter *A* represents the main supporting-frame of my improved stove, 35 which may be of cast-iron or other suitable material, and is preferably perforated and ornamented, as shown in Figs. 2 and 4. It may be of circular form, as shown, or more or less elongated, or angular, if necessary. In this frame 40 is suspended the oil-reservoir *B*, which is a bowl-shaped vessel, provided at three (more or less) points with radially-projecting outer ears, *a*, through which are passed bolts *b*, or equivalent pins or screws, that extend also through 45 the upper flange, *d*, of the frame *A*. Thus the bowl or reservoir *B* is suspended within the frame *A*. In order to prevent heat from being communicated to the bowl *B* by its contact with the frame *A*, I interpose a washer or disk, 50 *e*, of cork, asbestos, or other suitable non-heat-conducting substance, between the flange *d* of

the frame *A* and the lug or ear *a* of the bowl, as is clearly shown in Fig. 1.

The oil-reservoir *B* is open on top, as clearly shown in Figs. 1 and 4, and has at one side a 55 projecting nozzle, *f*, which enters into a flue-like extension, *g*, of the frame *A*, as shown in Fig. 1. The flue-like extension *g* is closed on top by a swinging cover, *h*. When this cover *h* is swung aside, as indicated by dotted lines 60 in Fig. 2, it opens the top of the flue *g*, and gives access, therefore, to the open end of the extension *f* of the oil-reservoir. Thus the oil-reservoir can be filled at pleasure through these 65 extensions *f* and *g* without requiring the main body *D* of the stove to be turned aside.

I am aware that it is not new to provide oil-reservoirs with extensions through which they may be fed; but I believe it to be quite new to provide an oil-reservoir that is incased by 70 a surrounding frame with an extension, *f*, that enters an extension, *g*, of the frame itself, outside of the radius of the upper heating-chamber.

C is the cover of the oil-reservoir. This 75 cover is of annular form, and preferably bulged, as shown in Figs. 1 and 4. The object of this cover is to protect the contents of the oil-reservoir, and also to furnish a support for the drum that holds the wick-tubes and their operating mechanism and the diaphragm above said drum. Beyond that and the parts *o*, *p*, and *r*, hereinafter referred to, the cover *C* has nothing to support, because the heating-drum *D* of the stove is supported by a frame, *E*, 80 which is hinged, at *i*, to the frame *A*, and which is further supported on the frame *A* by projecting legs *j*, which are more clearly shown in Figs. 3 and 4. Thus the cover *C* does not take part in supporting the drum *D*, or any of the 85 attachments of said drum. I regard this as quite an important feature, because it enables me to secure the wick-tubes in the cover in the manner which I shall hereinafter describe, and for other obvious reasons. All strain is 90 taken from the oil-reservoir *B* by my construction of stove. The cover *C* has at one side a projection or hinge-piece, *l*, (see Figs. 2 and 4,) that enters a slot in the flange of the frame *A*, and on which hinge-piece the said cover *C* can 95 be swung up, as indicated by dotted lines in Fig. 4, after the drum *D* has been swung on 100

- its hinge *i* away from the top of the cover *C*. When the cover *C* is in its horizontal position it does not at any part rest on the reservoir *B*, but is entirely supported throughout by the 5 frame *A*, and being bulged, as shown, and at no point in contact with the reservoir *B*, there is an air-chamber, *m*, formed beneath the cover *C*, and above the oil-reservoir, which air-chamber communicates with the annular space *n*,
- 10 that directly surrounds the reservoir *B*, and thence with the open air through the apertures of the frame *A*. The cover *C*, as before stated, is of annular form, and has in the construction shown upwardly-projecting posts *o*, on 15 which rests the ring *p*, which supports the perforated diaphragm *F*, that admits atmospheric air to the flame or flames of the stove. Between the cover *C* and the ring *p* is ample space to allow the air to reach the said diaphragm.
- 20 The ring *p* is held fast by two (more or less) bolts, *r*, that extend from it downwardly through the cover *C*, or through inwardly-extending lugs of said cover, as shown in Fig. 4. These bolts *r* are drawn tight until the ring *p* 25 rests firmly on the supporting-posts *o*.
- The wick-tubes *G* are securely fastened in a sheet-metal drum, *H*, that has perforated walls *s*, and that rests on the cover *C*, the said sheet-metal drum *H* being of such size 30 as to close the opening in the top of the cover *C*. The drum *H* is held in place by the bolts *r*, and furnishes a further protection for preventing the oil from being overheated, inasmuch as an air-chamber is formed within said 35 drum *H*, and also because the air in said drum can always circulate through the perforated rim *s*. Beyond being secured to the said drum *H*, the wick-tubes have no further rigid connection with the stove, and when it is desired 40 to remove or repair them it is only necessary to lift off the cover *C*, unscrew the bolts *r*, and then have all the parts that are joined to the cover *C* in the stove separated for cleaning or repair. Being secured to an air-box, *H*, the 45 wick-tubes are not liable to communicate any heat to the oil-chamber, nor do they dip into the oil-chamber to such a depth as to be liable to come bodily in contact with the oil itself, at least as far as the most perfect construction of 50 the stove is concerned.
- I have described the box *H* as being made of sheet metal; but of course it may be made of any other suitable material.
- The drum *D*, which forms the heating-chamber 55 of the stove, has a door, *I*, at one side, said door containing a piece of mica, *t*, to allow the flame or flames to be seen without opening the drum.
- I desire it to be understood that when I men- 60 tion in this specification the "wick-tubes" I do not mean to limit myself to the use of more

than one wick-tube in a stove, nor, in fact, to any number, as all the features of my invention are applicable to stoves having single wick-tubes, as well as to stoves having more than 65 two wick-tubes; nor do I limit myself to any particular form of stove, which, as already stated, may be circular, oval, oblong, or even square.

I claim—

1. In a coal-oil stove, the combination of a supporting-frame, *A*, with a reservoir, *B*, suspended at two or more projecting points from said reservoir, and with non-conducting packing *e* between said projecting points and the 70 supporting-frame, substantially as described.

2. The combination of the oil-reservoir *B*, having projecting nozzle *f*, with the surrounding supporting-frame *A*, having flue-like extension *g*, into which the said nozzle *f* enters, 80 substantially as and for the purpose described.

3. The combination of the supporting-frame *A*, containing the suspended oil-vessel *B*, with the cover *C*, drum *H*, that holds the wick-tubes, and with the drum-frame *E*, which is hinged 85 to the frame *A*, and entirely supported thereon, so that the drum and its attachments will not be supported on the cover *C* nor on the drum *H*, substantially as described.

4. The combination of the supporting-frame 90 *A* with the suspended oil-reservoir *B*, and with the cover *C*, having projecting hinge-piece *l*, that enters a slot in the flange of the frame *A*, and with the drum *D*, which is separately hinged to the frame *A*, so that by folding the drum *D* 95 the cover *C* and the wick-tubes will be left undisturbed, substantially as specified.

5. The combination of the frame *A*, having air openings or apertures, with the suspended reservoir *B*, and with the cover *C*, all arranged 100 to form an air-space, *m*, between the cover and the reservoir, and a communication, *n*, between said air-space *m* and the outer air, substantially as specified.

6. In an oil-stove, the wick tube or tubes *G*, 105 carried by and fastened to a hollow drum, *H*, having perforated wall *s* and closed top and bottom, in combination with the annular cover *C* and reservoir *B*, the drum *H* resting directly on and closing the opening in said cover, substantially as specified.

7. In an oil-stove, the combination of the annular cover *C* of the oil-reservoir with the ring *p*, posts *o*, diaphragm *F*, wick-tubes *G*, hollow drum *H*, having perforated walls and 110 closed top and bottom, and bolts *r*, substantially as described.
